Int. Cl. D8—08
U.S. Cl. D8—235

FIG. 1 is a perspective view, from the underside, of a conduit clip embodying my new design wherein a conduit is shown in broken line and forms no part of the design.

FIG. 2 is a perspective view from the top of the conduit clip shown in FIG. 1.

FIG. 3 is an end elevational view of the conduit clip shown in FIG. 1.

FIG. 4 is a top plan view of the conduit clip shown in FIG. 1.

FIG. 5 is a side elevational view of the conduit clip shown in FIG. 1.

FIG. 6 is a bottom plan view of the conduit clip shown in FIG. 1.

I claim:

The ornamental design for a conduit clip, as shown and described.
